United States Patent Office

Des. 183,683
Patented Oct. 14, 1958

183,683

BADGE OR SIMILAR ARTICLE

Jesse Samuel Embree, Los Angeles, Calif.

Application September 21, 1956, Serial No. 43,027

Term of patent 7 years

(Cl. D29—2)

Fig. 1.

Fig. 2.

Fig. 1 is a front elevational view of a badge or similar article, showing my new design; and

Fig. 2 is a side elevational view thereof.

The rear of the article is substantially plain and unornamented. The dominant features of the design reside in the portion shown in full lines.

I claim:

The ornamental design for a badge or similar article, as shown and described.
